HELICAL COIL BUTT GROUND WINDING
MACHINE

Claude J. Terrell, Quincy, Ill.

Application January 31, 1947, Serial No. 725,626

3 Claims. (Cl. 153—64)

1

This invention relates to helical coil winding machines.

An object of the invention is to provide a machine by means of which helical coils may be formed.

Another object of the invention is to provide a helical coil winding machine which is designed to form soft drawn copper wire into a specified shape allowing the proper number of turns to meet the Rural Electrification Administration specifications for a butt coil type ground for use in grounding electric distribution and transmission poles.

A further object of the invention is to provide a helical coil winding machine having a rotatable drum upon which the coil is formed, and having power drive means including speed reduction means for forming the coils at high speed.

Still another object of the invention is to provide a helical coil winding machine which is simple in design, inexpensive to manufacture, and which is rapid and effective in operation.

Other objects and advantages of the invention will become apparent from the following description of a preferred embodiment thereof as illustrated in the accompanying drawings, and in which,

Figure 1 is a side elevational view of my improved machine,

Figure 2 is a fragmentary front elevation of the device as seen from the left side of Figure 1,

Figure 3 is a horizontal sectional view taken on line 3—3 of Figure 1,

Figure 4 is a vertical sectional view taken on line 4—4 of Figure 1,

Figure 5 is a horizontal sectional view taken on line 5—5 of Figure 4,

Figure 6 is a face view of one of the helical coils formed in the machine, and

Figure 7 is a side elevation of the coil shown in Figure 6.

In order to understand clearly the nature of the invention and the best means for carrying it out, reference may now be had to the drawings, in which like reference characters denote similar parts throughout the several views. As shown, there is a base member 10 supporting an upright post 12 having a lateral bore 14 for the reception of a bearing 16. A shaft 18 is journaled at its right hand end as seen in Figure 3 in the bearing 16, and extends through the hub 20 of a winding form drum 22, the hub being keyed on the shaft by means of a set screw 24.

The winding form drum 22 has a substantially cylindrical portion 26 with a right hand end 55

2

annular flange 28, and its left hand portion 30 is conical between locations 32 and 34, the conical portion having continuous helical ribs 36, which furnish support for the wire which is to be wound on the form. The left hand end of the shaft 18 is laterally recessed at 38.

Rotatable mandrels 40 and 42 are keyed on rotatable shafts 44 and 46 which are journaled in bearings formed in support members 48 and 50 which are pivotally interconnected and supported upon a pivot pin 52 extending into the upright post 12. The links 54 and 56 are pivotally connected by pin 58 at their upper ends and are connected by pivot pins 60 and 62 at their lower ends of the upper ends of the support members 48 and 50, a tension spring 64 serving to draw the members and their mandrels together out of contact with the inner face surface of the cylindrical drum 26.

20. The shafts 44 and 46 are rotated by means of sheaves 66 and 68 which are keyed on their outer ends, the sheaves being interconnected by means of a belt 70. A pull rod 72 is pinned at its upper end to pin 58 and is connected at its lower end to a treadle lever 74 having a pedal 76 and pivoted at 78, whereby depression of the pedal spreads the mandrels apart to engage the inner drum surface of the drum 26, to rotate it as the mandrels are rotated.

25. 30. A larger sheave 80 is also fast on the shaft 44 and is driven by means of a belt 82 also encircling the smaller sheave 84 which is fast on a shaft 86 and also carries a larger sheave 88 which is rotatable therewith. A power belt 90 encircles 35. the sheave 88, and also the drive pulley of a motor, not shown, whereby the machine is operated. The diameters of the various sheaves are so arranged and related, that a motor having a relatively high speed, will have the speed reduced sufficiently for the purposes of the machine by the time it reaches the mandrels 40 and 42, which drive the winding drum.

35. 40. The drum flange 28 has teeth 92 formed on its right end surface as seen in Figures 1 and 5, which are engageable by the arm 94 of a hinge dog 96 the stationary arm of which is secured to frame 12 by screws 98. A leaf spring 100 biases the arm 94 into engagement with the teeth 92.

45. 50. In operation, the motor is started, driving the sheaves and rotating the mandrels. The wire to be wound has one end inserted into the projecting eye 94 on the conical drum, and then the pedal 76 is depressed, which expands the mandrels apart to engage the inner drum surface, rotating the drum, and the wire is wound on the helical ribs 36 to-

ward the apex of the conical drum at 96. Then the pedal 76 is elevated, stopping the drum and the wire is brought up around the left end of the shaft end 96 as at 98 in Figure 6, and then bent across the recess 38 as at 100 in Figure 6.

The wire is then bent along as at 102 and around eye 104, thence back along 106 and against the side of shaft end 96 and down on the opposite side along 108 and around eye 110, thence around as at 112 and up onto the cylindrical portion 26 of the drum to wind the cylindrical portion 14 of the coil, which takes care of the extra wire which is to be extended to the top of the pole.

Although I have described a preferred embodiment of my invention in specific terms, it is to be understood that various changes may be made in size, shape, materials and arrangement without departing from the spirit and scope of the invention as claimed.

I claim:

1. A device for forming helical ground coils, comprising a support, a rotary shaft journaled upon the support, a winding drum mounted upon the shaft for rotation therewith, the winding drum comprising a hub for engagement upon the shaft; an axial cylindrical portion spaced radially outwardly from the hub and including an inner annular flange having teeth formed thereon, a conically tapered portion arranged axially outwardly of the cylindrical portion and having an external spiral formation thereon, the outer end of the rotary shaft extending axially beyond the outer end of the conically tapered portion, an element mounted upon the support and engaging the teeth to prevent backward rotation of the winding drum, driving connecting means for rotating the winding drum, and manually operable means to control the rotation of the drum.

2. A device for forming helical ground coils, comprising a support, a rotary shaft journaled upon the support, a winding drum mounted upon the shaft for rotation therewith, said drum comprising an inner hub for engagement with the shaft, an axial cylindrical portion spaced radially outwardly from the hub and including an inner annular flange having end teeth formed thereon, a conically tapered portion secured to the cylindrical portion and extending axially outwardly thereof and having a spiral rib formed thereon, the outer end of the rotary shaft projecting past

the outer end of the conically tapered portion and having a transverse flat face to engage the coil wound upon the drum, elements secured to the winding drum for engaging the coil wound thereon to facilitate forming the same, a pivoted dog mounted upon the support and engaging the teeth to prevent backward rotation of the drum, rotary driving members arranged between the hub and inner surface of the cylindrical portion and shift-

able into and out of contact with the cylindrical portion for rotating the drum, manually operable means to shift the driving members, and power operated driving connecting means to rotate the driving members.

3. A device for forming helical ground coils, comprising an upstanding support, a substantially horizontal rotary shaft journaled upon the support, a rotary winding drum mounted upon the shaft for rotation therewith, the drum comprising a tubular hub to engage the shaft and an axial cylindrical portion spaced radially outwardly of the hub for receiving a part of the coil, a conically tapered portion secured to the cylindrical portion and extending axially thereof and having a spiral element formed therein to guide a portion of the coil, the outer end of the shaft projecting beyond the outer end of the drum and having a flat formed thereon to engage the coil to facilitate forming the same, diametrically oppositely arranged elements secured to the conically tapered portion near its junction with the cylindrical portion, the elements engaging the coil in the formation of the same, and power operated manually controllable means to rotate the drum.
